US0D1070740S

(12) **United States Design Patent** (10) **Patent No.:** **US D1,070,740 S**
(45) **Date of Patent:** **** Apr. 15, 2025**

(54) **BATTERY PACK**

- (71) Applicant: **Greenworks (Jiangsu) Co., Ltd**,
Jiangsu (CN)
- (72) Inventors: **Jiatao Li**, Jiangsu (CN); **Jie Kuang**,
Jiangsu (CN)
- (73) Assignee: **Greenworks (Jiangsu) Co., Ltd**,
Changzhou (CN)

(**) Term: **15 Years**

(21) Appl. No.: **29/884,775**

(22) Filed: **Feb. 16, 2023**

(30) **Foreign Application Priority Data**

Primary Examiner — April Rivas

Assistant Examiner — Robin L Hammonds

(57) **CLAIM**

The ornamental design for a battery pack as shown and described.

DESCRIPTION

FIG. 1 is a top, front and right side perspective view of a battery pack showing our new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of portion 9 in FIG. 1.

The dash-dash broken lines in the drawings illustrate portions of the battery pack which form no part of the claimed design. The dot-dash broken lines illustrate the boundaries of the enlarged view and form no part of the claimed design.

1 Claim, 9 Drawing Sheets
